UNITED STATES PATENT OFFICE.

JOSEPH TCHERNIAC, OF FREIBURG, GERMANY, ASSIGNOR OF ONE-HALF TO
ERNEST THEOPHILUS LIEFIELD, OF NEW HAVEN, CONNECTICUT.

FRUIT-JAR.

SPECIFICATION forming part of Letters Patent No. 710,818, dated October 7, 1902.

Application filed May 2, 1902. Serial No. 105,600. (No model.)

To all whom it may concern:

Be it known that I, JOSEPH TCHERNIAC, a citizen of the Republic of France, and a resident of Freiburg, in the Grand Duchy of 5 Baden, Empire of Germany, have invented a new and useful Improvement in Fruit-Jars; and I do hereby declare the following, when taken in connection with the accompanying drawings, and the figures of reference marked 10 thereon, to be a full, clear, and exact description of the same, and which said drawings constitute part of this specification, and represent, in—

Figure 1, a broken view, in side elevation, of 15 a fruit-jar constructed in accordance with my invention; Fig. 2, a detached plan view of the cap and clip, the broken lines in this figure showing the horizontal movement of the cap in being applied to or removed from the 20 jar; Fig. 3, a broken view of the jar in vertical section.

My invention relates to an improvement in fruit-jars, the object being to produce at a low cost of manufacture a simple, durable, convenient, and effective jar constructed with 25 particular reference to avoiding the use of rubber gaskets and to preventing the entrance into the contents of the jar of any germs.

With these ends in view my invention consists in a fruit-jar having certain details of 30 construction and combinations of parts, as will be hereinafter described, and pointed out in the claim.

In carrying out my invention I form a flange 35 or overhanging rim 2 at the top of the neck 3 of an ordinary glass jar 4. The upper face of this rim is ground perfectly flat in a horizontal plane, so as to form a sealing-surface 5, which forms a smooth bearing for and a 40 germ-proof seal with the outer portion of the lower surface of a sliding disk-like cover or cap 6, made of porcelain, glass, or some other vitrified material. Preparatory to closing the jar the sealing-surface 5 is preferably smeared 45 with vaseline or equivalent substance, after which the cap is secured in place. This may or may not seal the jar against the entrance of air; but it will seal the jar against the entrance into it of all germs. To secure the 50 cap in place, I employ a fastener in the form

of a clip made from a single piece of wire and consisting of a straight reach or body portion 7 and two downwardly-turned arms 8, the ends of which terminate in eyes 9, formed by coiling the ends of the wire inward. The 55 reach 7 of the clip enters a groove 10, extending diametrically across the upper surface of the cap, while the eyes 9 engage with the bevel 11, formed upon the outer edge of the rim 2. The clip is proportioned so that it 60 cannot be applied to the jar and cap without putting it under enough tension to cause it to constantly draw the cap down upon the sealing-surface 5. In closing the jar or in opening it the cap or cover is slid horizontally on the rim. The clip is applied to the cap before the same is slid upon the rim, with the beveled edge of which the eyes of its arms will engage, so that the body or reach of the clip will turn somewhat and the arms lag behind. 70 Then when the cap is fully in place the arms will be pushed forward until they stand in a vertical plane. When the cap is slid in one direction or the other to remove it from the jar, the arms will lag behind in 75 the opposite direction from which the cap is being moved.

It will be seen from the foregoing description that my improved jar requires only two independent parts—namely, the cap and the 80 clip—and that the jar and the cap and the clip are of extremely simple construction and operation. While it is not claimed that the jar when closed is strictly air-tight it is claimed that it is very nearly air-tight and 85 quite germ-proof and that fruits contained in the jar will be preserved for a long time without loss of freshness of flavor and without any of the impairment of flavor which invariably accompanies the use of rubber in any form 90 in connection with the sealing of a jar containing fruit or fruit-juices.

Having fully described my invention, what I claim as new, and desire to secure by Letters Patent, is—

The combination with a jar having its neck formed with a rim, the upper surface of which is ground in a horizontal plane to form a perfectly flat sealing-surface, and the outer edge of which is beveled, of a sliding disk-like vit- 100

rified cap having its lower surface made smooth to form a close joint with the said ground sealing-surface and having a groove extending across its upper surface, and a 5 wire clip comprising a reach which enters the said groove, and two downwardly-extending arms which engage under tension with the said beveled edge, whereby the cap is drawn down into close engagement with the said 10 ground sealing-surface, on which the cap is

slid horizontally in closing and in opening the jar.

In testimony whereof I have signed this specification in the presence of two subscribing witnesses.

JOSEPH TCHERNIAC.
